TONGS FOR SUSPENDING A PAINT CAN
OR THE LIKE

Raymond C. Morris, Dayton, Ky.

Application May 1, 1947, Serial No. 745,168

4 Claims. (Cl. 294—93)

1

My invention relates to a pair of tongs for suspending a paint can or the like from the rung of a step ladder.

While it used to be the common practice to provide paint cans with bails with which to carry them and which could be used to suspend the can from the rung of a step ladder, while in use, the modern practice is to provide paint cans without any bails. However, the tops of the cans are so constructed that there is an inwardly projecting annular rim which frictionally holds the top of the can, but which remains on the can after the lid is removed.

It is an object of my invention to provide a pair of tongs which are adjustable to any normal size of paint can and which hooks under the edge of the inwardly projecting rim to suspend the same.

It is a further object of my invention to provide a pair of tongs for suspending a paint can as described above which is cheaply and easily manufactured, but which efficiently and safely holds the can when suspended from the rung of a step ladder.

It is a further object of my invention to provide a pair of tongs for suspending a paint can which may be quickly and readily attached to the can and removed from the same when not needed.

These and other objects of my invention which will be set forth hereinafter or will be apparent to one skilled in the art upon reading these specifications, I accomplish by that certain construction and arrangement of parts of which I shall now describe an exemplary embodiment. Reference is now made to the drawings which form a part thereof, and in which:

Figure 1 is a front elevation of my novel tongs in place suspending a paint can, the paint can being in section.

Figure 2 is a rear elevation of my novel tongs.

Figure 3 is a side elevation of the tongs shown in Figure 2.

Figure 4 is a cross section of the tongs shown in Figure 2, taken on a section line 4—4 in Figure 2.

Figure 5 is a front elevation of the tongs showing the adjustability of the distance between the tongs.

Figure 6 is a perspective view of the journal for use with my tongs.

Briefly, in the practice of my invention, I provide a pair of tongs formed of arms in the configuration of the letter L. One end of the tongs are pintled to a fixture carrying a journal. A rod is slideable through the journal and has a ring at one end, embracing the tong arms where they

2

cross. The other end of the rod carries means for attaching it to a chain which in turn may be attached to the rung of a ladder. Actuation of the rod determines the distance between the two hooks on the terminal of the arms.

Referring to the drawings, I provide two arms 1 and 2 which cross each other at 3, and are preferably L-shaped in configuration. The end of the short leg of the L contains an eye 4, which 10 rides over a pintle 5. In the construction I have shown, the pintle 5 is in the form of a rivet. However, other forms of pintles may be used. The pintle 5 is mounted on a bracket 6 which contains journal holes 7. While I have shown the 15 bracket 6 in the form of a journal, other configurations are within the contemplation of my invention. I preferably provide a disc-like member 8 placed between the rivet head 9 and the eyes 4 to insure smooth operation of the arms 20 on the pintle 5. However, the disc 8 may be configured differently or may be a part of the pintle. The terminals of the arms 1 and 2 opposite the eyes 4 carry hooks 10 and 11.

There is a rod 12 which is journaled in the holes 25 7 of the bracket 6 and one end is formed into a ring 13 which embraces the arms 1 and 2 at their crossing point. The other end of the rod 12 is formed into a loop or hook 14 which may be attached to a chain 15 either by hooking to the 30 end of the same or preferably by sliding over a hook 16 on the end of the chain 15. The other end of the chain 15 carries a large hook 17 which may be placed over the rung 18 of a step ladder.

The usual paint can or similar can has a wall 35 19 and an inwardly projecting flange portion 20.

In operation, the cover of the can is removed and the ends of the arms 1 and 2 carrying the hooks 10 and 11 are inserted in the can opening. The rod 12 is then moved vertically which forces 40 the hooks 10 and 11 apart until they hook under the flange 20 of the paint can. The chain 15 is then attached to the end 14 of the rod 12 and hooked to the rung 18 of the ladder by the hook 17. The weight of the paint tends to slide the bracket 6 carrying the pintle 5 downwardly on the rod 12 which in turn tends to force the ends of the rods 1 and 2 carrying the hooks 10 and 11 apart. This insures the gripping of the paint can under the projecting rim 20 as is apparent 45 from the drawings.

When it is desirable to remove the tongs from a paint can the rod 12 is manually slid downwardly in the journal 7 which brings the hooks 10 and 11 together and permits their removal 50 from the opening of the paint can.

I preferably place a hook 16 on the end of the chain 15 so that the chain 15 with the hooks 17 and 16 may be used to support a paint can having a bail on the rung of a ladder by inserting the hook 16 around the bail.

While I have shown both of the arms 1 and 2 mounted on a single pintle 5 attached to the bracket 6, it is within the contemplation of my invention to provide two pintles on the bracket 6 and mount a single arm on each pintle.

The disc 8 while insuring the smooth operation of the device may also be used for carrying advertising matter or the like.

From the above, it is apparent that I have provided tongs for suspending a paint can or any other container having an inwardly projecting rim to the rung of a ladder or any similar support from which it is desirable to hang the can.

It is to be understood that modification may be made in my invention without departing from the spirit thereof, and I do not intend to limit myself otherwise than as pointed out in the claims which follow.

Having thus described my invention, what I claim as new and desire to secure by Letters Patent is:

1. Tongs for suspending a can having an inwardly projecting flange, comprising a channel-shaped bracket having aligned holes in the legs and a pintle mounted on the outside of the base, a disc on the end of the pintle, two L-shaped arms having eye-shaped ends surrounding the pintle between the channel base and the disc, said arms crossing each other at a point, a rod terminating in a loop embracing said arms at their point of crossing and journaled in said holes in the channel legs, the other end of said rod connected to a hook and the arms terminating in flange-engaging hooks for the purpose described.

2. Tongs for suspending a paint can or the like having an inwardly projecting rim, comprising two crossed arms having one end mounted on a

5 pintle and the other end terminating in a rim engaging hook, a rod terminating in a loop embracing both arms at their point of crossing, said rod sliding through aligned holes in the legs of

5 a channel shaped bracket mounted on one end of the pintle and having chain attaching means at the other end for the purpose described.

3. Tongs for suspending a paint can or the like having an inwardly projecting rim, comprising

10 two crossed arms having one end mounted on a pintle and the other end terminating in a rim engaging hook, a rod terminating in a loop embracing both arms at their point of crossing, said rod sliding through aligned holes in the legs of

15 a channel shaped bracket mounted on one end of the pintle and having chain attaching means at the other end for the purpose described, a portion of said arms between the loop and the pintle being bent.

4. Tongs for suspending a paint can or the like having an inwardly projecting rim comprising

20 two crossed arms having one end rotatably mounted on a channel shaped bracket and the other end terminating in a rim engaging hook, a rod terminating in a loop embracing said arms at their point of crossing, said rod journaled in holes in the channel legs of the bracket and having chain attaching means to the other end for the purpose described.
